UNITED STATES PATENT OFFICE.

DORSEY FROST ASBURY, OF WASHINGTON, DISTRICT OF COLUMBIA, ASSIGNOR TO
UNITED STATES ORDNANCE COMPANY, OF WASHINGTON, DISTRICT OF COLUM-
BIA, A CORPORATION OF VIRGINIA.

BREECH CLOSURE.

1,410,525.

Specification of Letters Patent. Patented Mar. 21, 1922.

Application filed November 16, 1918. Serial No. 262,815.

To all whom it may concern:

Be it known that I, DORSEY F. ASBURY, a citizen of the United States, residing at Washington, District of Columbia, have invented certain new and useful Improvements in Breech Closures; and I do hereby declare the following to be a full, clear, and exact description of the invention, such as will enable those skilled in the art to which it 10 appertains to make and use the same.

My invention relates to breech closures and particularly to the type described and broadly claimed in my copending application filed October 30, 1918, and serially numbered 15 260,339.

My present invention, broadly speaking, attains the objects set forth in respect to my said copending application, while, more particularly speaking the objects of my present 20 invention are to provide a single means for utilizing energy stored in the breech plug to produce all movements of the plug's opening and closing cycle except the unlocking movement of the plug; to provide a cam and 25 a cam follower coating therewith to produce said movements of the plug; to provide a cam groove and a cam follower for producing said movements of the plug, the cam follower traveling in said groove during all 30 movements of the plug; to provide a breech plug adapted to be unlocked by either of two movements; to provide a breech plug adapted to be unlocked by either of two 35 movements, and means for preventing one of the unlocking movements at a predetermined time; to provide automatically operated means for effecting one unlocking movement of the plug and manually operated means for effecting the other unlocking 40 movement; to provide a breech structure wherein the breech plug is movable in the same direction at the beginning and end of its opening and closing cycle to effect unlocking and locking thereof respectively; to 45 provide a breech closure wherein a single means utilizes unlocking movement of an element of the closure to open, close and lock the closure; to provide a breech structure wherein the breech plug is adapted to be 50 unlocked by movement in one direction and locked by movement in the same direction; to provide a breech plug adapted to be

locked by movement in one direction and unlocked by movement in the same direction and also by movement in the reverse direction; to provide means utilizing the unlocking movement of the plug to produce all other movements thereof with respect to the gun; to provide a member fixed to the plug acting against a member on the mount to stop the plug in locked position whether the gun is home or not; and to provide an improved structure for facilitating the application and removal of the breech plug to and from the gun.

I will describe my invention as applied to a gun supported by a mount in which it is adapted to recoil, the gun embodying a rotatable and longitudinally movable breech plug; but it will be understood that my invention in its fullest aspect and elementary parts thereof is applicable to other forms of guns and breech closures, and that the invention can be altered and varied in a pronounced manner without departing from the scope of the claims, the drawings and description forming a part hereof being merely illustrative of one method of carrying my invention into practice.

In describing my invention reference will be had to the accompanying drawings wherein like characters of reference denote corresponding parts in the several views, and in which—

Fig. 1, is a vertical section through the breech end of a gun embodying my invention, the breech plug being shown in its home or locked position;

Fig. 2, a view similar to Fig. 1 with the gun recoiled to a position it would occupy just as the automatic unlocking movement of the breech plug is instituted;

Fig. 3, a view similar to Fig. 1 showing the gun in full recoil position and the breech plug in full open position;

Fig. 4, a section on the line 4—4 of Fig. 1 looking down;

Fig. 5, a similar section looking up;
Fig. 6, a section on the line 6—6 of Fig. 1;
Fig. 7, a section on the line 7—7 of Fig. 1;
Fig. 8, a section on the line 8—8 of Fig. 1;
Fig. 9, a section on the line 9—9 of Fig. 1;
Fig. 10, a section on the line 10—10 of Fig. 1;

- Fig. 11, a section on the line 11—11 of Fig. 1;
Fig. 12, a detail perspective view of the breech end of the gun;
5 Fig. 13, a perspective view of the breech plug with the operating handle removed;
Fig. 14, a perspective view of the breech plug in another position, the ejector being shown in dotted lines;
10 Fig. 15, a front end view of the breech plug; and
Fig. 16, a perspective view of the ejector.
Referring to the drawings 10 indicates a recoil mount and 11 the gun arranged to slide in said mount during recoil and counter recoil, said gun being connected with a suitable recoil brake (not shown) by rod 12. In order to facilitate the disconnection of the gun from the rod 12 said rod is secured to a 20 connecting block 13 which seats in a recess 14 formed in the gun and is detachably held to the latter by a screw 15. By removing this screw it will be obvious that the connecting block 13 can be readily disengaged from the recess 14 and the gun 11 thereby disconnected from the rod 12. A breech chamber A is provided at the rear end of the gun and comprises a forward portion 16 and an enlarged rear portion 17. Mounted for rotation and 30 reciprocation in the breech chamber A is a breech plug B the rear end of which is enlarged by portions 18 and 19 so as to properly support the rear end of the breech plug in the portion 17 of the breech chamber during 35 the operation of the plug. The enlarged portions 18 and 19 of the breech plug are separated to form a longitudinal groove 20 for a purpose that will presently appear, while one edge of the portion 19 is shaped to form a 40 cam 21 adapted to coact with a cam follower on the mount to be presently referred to. The breech plug B is also provided with oppositely disposed locking lugs 22 which coact with locking lugs 23 formed on the gun.
45 To unlock the breech plug it is only necessary to rotate the same so as to bring the lugs 22 out of alignment with the lugs 23 and this unlocked status can be produced by rotation of the plug in either direction 50 unless otherwise prevented. Also mounted on the plug is an extractor 24 of the usual and well known construction. The forward end of the plug B is provided with a circumferential cut-away portion 25 and inwardly 55 of this cut-away portion 25 the plug is provided with a circumferential groove 26 both ends of which have a forwardly extending enlarged portions 27. An ejector member C is carried by the plug B and is provided at 60 its ends with lateral extensions 28 and 29 which are disposed respectively in the groove 26 and cut-away portion 25, the body of the ejector during longitudinal movements of the plug B sliding in a groove 30 65 formed in the gun 11. In order to impart

ejecting movement to the element C during rearward movement of the breech plug I mount in the gun an actuating screw 31 disposed in line with the rear end of the groove 30. When the plug B is unlocked through 70 the medium of the coaction of the cam 21 and the cam follower to be presently referred to, the extension 28 of the ejector member is brought into line with one enlargement 27 of the groove 26 and upon rearward movement of the breech plug the rear end of the ejector element C engages the screw 31 and drives the ejector element forward sharply to effect the ejection of the empty cartridge case. When the breech plug is automatically returned home and locked in a manner to be hereinafter described the beveled wall 32 of said enlargement 27 coacts with extension 28 to draw the ejector to the rear when the extension enters the groove 26 and 85 the ejector assumes its original position.

The gun 11 is provided on its lower side with a longitudinal slot 33 opening through its rear and projecting into this slot is a plate 34 detachably secured to the mount 10 90 by screws 35. The plate 34 is provided with a plurality of vertical passages 36, 37 and 38 in which is detachably and selectively secured a pintle 39 carrying on its upper end a roller 40 constituting a cam follower adapted for coacting with cam 21 on the breech plug during recoil of the gun to automatically effect unlocking movement of the plug. While in this instance I have shown the plate 34 provided with three vertical passages 100 for the selective reception of the pintle 39 it will be obvious that the number of such passages can be increased if desired. By moving the pintle 39 from one vertical passage to the other it will be apparent that the 105 position of the plug B in respect to the mount when the automatic unlocking movement is imparted thereto can be varied. By mounting the cam follower 40 on a plate detachably secured to the mount I render the 110 removal of the gun from the mount a very simple operation in that it only requires the removal of the connecting block 13 in the manner heretofore described and the removal of the plate 34 from the mount. 115

To accomplish the automatic operation of the plug B to open and closed positions I provide in the wall of the portion 17 of the breech chamber A an endless cam groove D forming a plurality of effective cam surfaces 120 41, 42, 43 and 44, said groove including substantially straight side portions 45 and 46. Mounted on the enlargement 18 of the breech plug B is a cam roller or follower 47 which travels constantly in the groove D and coacts successively with the cam surfaces 41, 42, 43 and 44 to utilize automatic unlocking movement of the breech plug to open, close and lock the plug. In other words I provide a single means for utilizing energy 125 130

stored in the plug to produce all movements of the plug's opening and closing cycle except the unlocking movement of the plug.

In operation, as soon as the gun is fired it 5 recoils in the mount 10 and during this recoil the cam follower 40 coacts with the cam 21 and imparts unlocking movement to the plug B. After this unlocking movement of the plug the cam follower 47 coacts with the 10 cam surface 41 to change the rotative movement of the plug to longitudinal movement and the follower moves in the side portion 45 of the groove D. When the plug almost reaches full open position the follower 47 15 coacts with the cam surface 42 to change the longitudinal movement of the plug to rotative movement, such change being completed when the plug is in full open position. This rotative movement of the plug is then 20 changed to forward longitudinal movement by coaction of the follower 47 with the cam surface 43, the follower then moving in the side portion 46 of the groove D until the breech plug is almost home. Finally, the 25 follower 47 coacts with the cam surface 44 to change the forward longitudinal movement of the plug to rotative locking movement and thereby complete the opening and closing cycle of the plug. It will be ob-

30 served that the locking movement of the plug B at the end of the opening and closing cycle is in the same direction as the unlocking movement at the beginning of said cycle. It will be further observed in the operation 35 just described that the position of the groove 20 and the functioning of the parts is such that when the breech plug partakes of its longitudinal movement the groove is disposed in line with the follower 40 so that 40 such forward longitudinal movement of the plug will not be interfered with.

Secured to the rear end of the plug B and extending through the rear end of the breech chamber is a handle 48 whereby the plug B 45 may be manually unlocked, such manual unlocking being accomplished by rotation of the plug in a direction opposite to that in which the plug is rotated when automatically unlocked. When the plug is manually 50 unlocked the groove 20 is also brought into alignment with the follower 40 so that the rearward longitudinal movement of the plug will not be interfered with. The complete operation of the plug can of course be effected manually by producing the necessary 55 movements required by the travel of the follower 47 in the groove D. If it is desired to remove the plug B from the gun it is only necessary to first remove the screw 31 60 and then manually unlock the plug and move the same to the rear. By then reversing the rotation of the plug from its previous unlocking rotation the follower 47 can be brought into line with a run-out 49 and 65 the plug readily removed.

It will be noted that the circumscribing portion of the groove D which connects the cam surfaces 42 and 43 serves to delay the closing movement of the plug and such delay can be varied by varying the length of 70 such circumscribing portion.

In order to stop the automatic locking movement of the plug B I provide the handle 48 with a pallet 50 which engages the follower 40, said pallet also serving to prevent one unlocking movement of the plug 75 when the gun is at battery.

Cartridges are fed to the gun by gravity or a spring from a magazine 51 carried by the mount in substantially the same manner 80 as that described in my aforesaid copending application.

It will be noted that when I refer in the claims to a breech closure including a unitary mass or a breech closure formed of a 85 single unitary mass such expression shall be construed to cover and define mass constituted by a single piece or mass constituted by more than one piece each fixed in respect to the other.

90 I claim:

1. In a gun, a movable breech closure including a unitary mass energized by the initiation of the cycle of operation of the breech closure, and means thereafter operated solely by the energy stored in and delivered from said unitary mass to produce all the remaining movements of the closure in its cycle of operation.

2. In a gun, a movable breech closure including a unitary mass initially energized by unlocking movement of the closure, and means thereafter operated solely by energy stored in and delivered from said unitary mass to produce all the movements of the closure following said unlocking movement.

3. In a gun, a movable breech closure including a unitary mass energized by the initiation of the cycle of operation of the breech closure, and cam means thereafter operated solely by energy stored in and delivered from said unitary mass to produce all the remaining movements of the closure in its cycle of operation.

4. In a gun, a movable breech closure including a unitary mass energized by the initiation of the cycle of operation of the breech closure, and means thereafter operated solely by the energy stored in and delivered from said unitary mass to produce all the remaining movements of the closure in its cycle of operation, said means comprising a cooperating cam and cam follower, one of which is on the gun and the other on the unitary mass.

5. In a gun, a movable breech closure formed of a single unitary mass energized by the initiation of the cycle of operation of the closure, and means thereafter operated solely by the energy stored in and de-

90

- livered from said single unitary mass to produce all the remaining movements of the closure in its cycle of operation.
6. In a gun, a movable breech closure formed of a single unitary mass energized by the initiation of the cycle of operation of the closure, and cam means thereafter operated solely by the energy stored in and delivered from said single unitary mass to produce all the remaining movements of the closure in its cycle of operation.
7. In a gun, a longitudinally movable and rotatable breech closure formed of a single unitary mass energized by the initiation of the cycle of operation of the closure, and means thereafter operated solely by the energy stored in and delivered from said single unitary mass to produce all the remaining movements of the closure in its cycle of operation.
8. In a gun, a longitudinally movable and rotatable breech closure formed of a single unitary mass energized by the initiation of the cycle of operation of the closure, and cam means thereafter operated solely by the energy stored in and delivered from said single unitary mass to produce all the remaining movements of the closure in its cycle of operation.
9. In a recoil gun, a rotatable plug movable longitudinally with respect to the gun, and a cam and cam follower one of which is on a recoiling part of the gun and the other on the plug, said cam and cam follower co-acting after the institution of the unlocking movement of the plug to produce all the remaining movements thereof.
10. In a recoil gun, a rotatable plug movable longitudinally with respect to the gun, a cam on a recoiling part of the gun, and a cam follower on the plug coacting with the cam on the gun after the institution of the unlocking movement of the plug to produce all the remaining movements thereof.
11. In a recoil gun, a movable plug, means fixed relatively to the plug, and means fixed relatively to a recoiling part of the gun coacting with the first named means to produce all movements of the plug following the plug's unlocking movement.
12. In a gun, a longitudinally movable and rotatable breech plug, means for locking the plug against longitudinal movement relative to the gun releasable by rotation of the plug in either of two directions, and means for preventing one of the releasing movements of the plug at a predetermined time.
13. In a gun, a longitudinally movable and rotatable breech plug, means for locking the plug against longitudinal movement relative to the gun releasable by rotation of the plug in either of two directions, automatically operated means for effecting one releasing movement, and manually operated means for effecting the other releasing movement.
14. In a recoil gun, a longitudinally movable and rotatable breech bolt having a roller thereon reacting directly against a recoiling part of the gun when the bolt is energized to open, close and lock the bolt, and means for energizing the bolt.
15. In a recoil gun, a longitudinally movable and rotatable breech bolt, a cam device utilizing the energy derived from the unlocking movement of the bolt to open, close and lock said bolt, said cam device comprising a groove forming a plurality of cam surfaces and a cam follower traveling in said groove and coacting successively with said surfaces to operate the bolt, one of the elements of the cam device being located on a recoiling part of the gun and the other on the bolt.
16. The combination of a mount, a gun adapted to recoil on said mount, a breech plug, a cam on the plug, a cam follower on the mount coacting with the cam to impart unlock-movement to the plug during recoil and adjustable relatively to the mount to vary the position of the plug in respect to the mount when the unlocking movement is imparted thereto.
17. The combination of a mount, a gun adapted to recoil on said mount, a rotatable and longitudinally movable breech plug, a cam on the plug, a plate removably secured to the mount and a cam follower on the plate coacting with the cam during recoil to impart unlocking rotation to the plug.
18. The combination of a mount, a gun adapted to recoil on said mount, a rotatable and longitudinally movable breech plug having opposite unlocked positions, a cam on the plug, a cam follower on the mount coacting with the cam during recoil to automatically move the plug to one unlocked position, manually operated means for moving the plug to the other unlocked position, said plug having a longitudinal groove aligning with the follower in the manual unlocked position to permit manual removal of the plug from the gun.
19. The combination of a mount, a gun adapted to recoil on said mount, a rotatable and longitudinally movable breech plug, a cam on the plug, a cam follower on the mount coacting with the cam during recoil to automatically move the plug to unlocked position, means for utilizing the unlocking movement of the plug to effect the latter's complete operation, said plug having a longitudinal groove aligning with the follower during its closing to permit free closing movement of the plug.
20. The combination of a mount, a gun adapted to recoil on said mount, a rotatable and longitudinally movable breech plug having opposite unlocking movements, a

cam on the plug, a cam follower on the mount coacting with the cam during recoil to move the plug to one unlocked position, means for utilizing the automatic unlocking movement of the plug to effect the latter's complete operation, manually operated means for moving the plug to its other unlocked position, said plug having a longitudinal groove alining with the follower during automatic closing to permit free closing

movement of said plug, and when manually unlocked to permit manual removal of the plug.

In testimony whereof I affix my signature in the presence of two witnesses.
